UNITED STATES PATENT OFFICE.

LESTER W. BURTON, OF ROCHESTER, NEW YORK.

DESIGN FOR AN ADVERTISING-DESK.

Specification forming part of Design No. 5,214, dated August 22, 1871.

To all whom it may concern:

Be it known that I, LESTER W. BURTON, of the city of Rochester, in the county of Monroe and State of New York, have invented or produced a new and original Design for an Advertising Writing-Table, of which the following is a specification:

My improved design consists of a writing-table having two inclined surfaces or leaves, with a central raised partition extending longitudinally from end to end, surmounted by separated frames of ornamental form, said partition and frames being both adapted to holding advertising-cards.

In the drawing, Figure 1 is a front elevation, and Fig. 2 an end elevation.

A is the table, resting on ornamental legs B. C C are the two inclined leaves or writing-surfaces. D is the central raised partition, which extends longitudinally from end to end. On top it is straight or in a plane the whole length; at the ends it is wedge-shaped or pyramidal in form. E E E are the separated frames or sections which surmount the partition, being of the ornamental form shown. The opposite sides of the partition and of the frames are formed with panels a a a a and b b b, which receive advertising-cards, which are secured by hinged lids with glass covers.

This table is especially adapted to hotels and public rooms, and presents an ornamental and beautiful appearance. The raised partition presents a separation between the two sides of the table, while the surmounting frames relieve the monotony of the plane-surface and give a pleasing effect. The parts are highly ornamented by carved and fancy work, as shown.

What I claim, and desire to secure by Letters Patent, is—

The design for the advertising writing-table, as herein shown.

In testimony whereof I have hereunto signed my name in the presence of two subscribing witnesses.
